[57] CLAIM

The ornamental design for bird figure, as shown and described.

DESCRIPTION

FIG. 1 is a right, front perspective view of a bird figure showing our new design.

FIG. 2 is a front view thereof.

FIG. 3 is a right side view thereof.

FIG. 4 is a top view thereof.

FIG. 5 is a bottom view thereof.

The design is substantially symmetrical from side to side, and the left side is accordingly a mirror image of the right side, shown in FIG. 3.
